US00D596563S

(12) **United States Design Patent**
Kitajima et al.

(10) **Patent No.:** US D596,563 S
(45) **Date of Patent:** ** Jul. 21, 2009

(54) **COIL UNIT**

(75) Inventors: **Yoshiaki Kitajima**, Tokyo (JP); **Atsushi Shoji**, Tokyo (JP); **Masatoshi Shindoh**, Tokyo (JP)

(73) Assignee: **TDK Corporation**, Tokyo (JP)

(**) Term: **14 Years**

(21) Appl. No.: **29/300,286**

(22) Filed: **Mar. 10, 2008**

(30) **Foreign Application Priority Data**

Oct. 15, 2007 (JP) 2007-028085

(51) **LOC (9) Cl.** 13-02

(52) **U.S. Cl.** D13/117
